UNITED STATES PATENT OFFICE

BERTHOLD NAGY, OF BROOKLYN, NEW YORK

ROD-DISK-CUTTING MACHINE

Application filed September 13, 1928. Serial No. 305,651.

This invention relates to machines for cutting disks of cork rods and similar materials and has for its main object to provide a device of the mentioned character which may 5 be easily, expeditiously and continuously fed while in operation.

Another object of this invention is to provide a device of the class mentioned in which means are incorporated whereby every cork rod will be automatically advanced every 10 time after a disk has been severed therefrom, while every rod is prevented from any movement between the consecutive advances of the same.

Other objects of my invention include the provision of means whereby the advances of the cork rods may be suspended when desired, as, for instance, when some repairing is to be done on the machine, also of means 20 to continuously and automatically sharpen a rotary knife used in the device and to provide an adjustable limit and support for the cork rods to follow the reducing width of the knife.

Still further objects of the invention will be apparent as the specification of the same proceeds.

With the above and other objects in view, features of the invention include a rotating ring the peripheral portion of which carries 30 a plurality of upstanding tubes each receiving a cork rod which projects through a hole in the ring and is stopped by a stationary table underneath the ring spaced apart therefrom. A rotating disk knife projects into the space between the ring and the table at one side thereof so as to slice off the disks from the lower ends of the rods. The rods are automatically advanced by weights 35 slideable around the tubes, each tube having two oppositely cut longitudinal slots into which project star wheels carried by and rotatable in the respective weight and engaging the rod. The star wheels are prevented from 40 rotation in one direction so as to bind the rod

to the weight when it is sliding downwards, but the rod is prevented from moving upwards by spring catches operative in one direction only so that when the weight is lifted before every cut, by a roller thereon and a 50 stationary cam intermittently engaging it, the weight will move upwardly in relation to the rod, the star wheels describing a partial rotation and rolling upwards on the rod, and the weight is again ready to sink, carrying the rod with it for a new feeding. A 55 second cam temporarily releases the spring catch on the rod at the moment it is desired to permit it to drop with the weight thereon, which is just before the new cut is to 60 be made.

With these and other objects in view, as will more fully appear as the description proceeds, the invention consists in certain 65 constructions, arrangements and combinations of the parts that I shall hereinafter fully describe and claim.

Changes and variations may be made in the construction of the parts within the limits of the claims without departing from the 70 spirit and scope of the invention.

For a full understanding of the invention, reference is to be had to the following description and accompanying drawings in which,

Fig. 1 is a plan view of the assembled device some tubes having been removed from their sockets in the ring;

Fig. 2 is a substantially central vertical sectional view of the assembled device on line 80 2-2, Fig. 1, portions of the same being left in side elevation;

Fig. 3 is a fragmentary side elevation of the rotating ring, the table thereunder being shown in section, on the line 3-3 of Fig. 1, 85 and showing the cam and associate mechanisms for releasing the lower spring catch on the rod before cutting a disk off of the same;

Fig. 4 is a fragmentary sectional elevation 90

along the center line of the circular row of tubes, the section line being indicated at 4—4 of Fig. 1;

Fig. 5 is another fragmentary sectional elevation taken at a perpendicular plane to the cylindrical section surface of Fig. 4, and indicated at 5—5 in said figure;

Fig. 6 is a fragmentary horizontal sectional elevation on the line 6—6 of Fig. 4, while

Fig. 7 is a detail side elevation of the execute and associated parts for elevating or dropping the cam for releasing the spring catches on the rods, the cover of it being removed, and

Fig. 8 is a horizontal section thereof on the line 8—8 of Fig. 7;

Fig. 9 is a fragmentary detail of the mechanism for constantly and automatically sharpening the knife;

Fig. 10 is a fragmentary detail of an adjustable support piece.

Referring now more closely to the drawings by characters of reference, the numeral 20 indicates the table of the device having the leg and frame structure 21 thereunder for strengthening the same and supporting it on the ground. Two vertical shafts 22 and 23 are arranged in the table side by side to 30 and at the necessary distance from one another, their purpose and construction to be more fully explained hereinafter.

The shaft 22 is stationary, the lower end thereof being secured to an arm 24 fastened 35 on a stationary part 25 of the frame structure 21. A rotatable sleeve 26 surrounds the shaft 22 and carries a bevel gear 27 formed at its lower end with an elongated hub sleeve 28 which is secured on the sleeve 26 by any 40 appropriate means, as by the key 29.

A hole 30 is provided in the table 20 for the shaft 22 and its associated parts and a stationary sleeve or tube 31 is secured in the hole by its flange 32 resting on the table 20.

A rotating disk 33, the main element of 45 my device, rests on the top of the stationary tube 31, by its central hub sleeve 34 and is secured to the inner sleeve 26; as for instance, by screws 35, to rotate therewith.

The stationary shaft 22 is suspended on 50 the sleeve 26 by a sleeve 36, secured to the top of the shaft by screws 37 and carrying a radial upwardly bent arm 38 which terminates in a cam 39, the construction and purpose of which will be explained more in detail hereinafter.

The rotating disk 33 has an upstanding 55 outer ring flange 40 which has a circular row of through-going holes 41 provided therein.

In the upper countersunk portion of each 60 hole 41 a tube 42 is secured, by screw 42^a, through which is pushed a cork rod 43. The upper end of each tube 42 is flared, as at 44, and carries a spring catch 45 the tip of

65 which projects through a slot into the tube

and is shaped in such a manner as to permit the cork rod 43 to be pushed downwardly into the tube but catch the same and prevent its movement in an upward direction.

A weight 46 surrounds each tube 42 and is slidable thereon as well as on a guide rod 47. The weight has two oppositely set longitudinal enlargements each of which shows a slot 48 into which is set a star wheel 49, rotatable in the weight. (One section of the weight in Fig. 2 is taken on two angularly different radial lines to show one wheel and the guide rod in full lines. See Fig. 5). The star wheels protrude into the tube through slots therein and their teeth engage the rod 43.

A stationary ring 50 is provided underneath the ring 33, and particularly the row of tubes 42, and is secured in an adjustable manner on the table 20 by bolts 51 and nuts 52, a right hand portion thereof being removed, as at 53.

A main shaft 54 is journaled, as at 25 and 55, in the frame 21 and is driven in an appropriate manner, as through the fast and loose belt pulleys 56 and 57. Bevel gear 27 meshes with gear 58 fast on the shaft while a second gear 59 secured on the shaft 54 engages the gear 60 secured to the shaft 23, as by a sleeve hub 61 and pin 62, or in any other suitable manner well known in the art.

Shaft 23 has a collar 63 secured thereon by which it rests on a stationary sleeve 64, set into an opening 65 in the table 20 and secured thereto by a flange 66 and screws 67. The shaft 23 is rotatable in the sleeve 64 and its upper portion carries a disk knife 68 set between two hubs 69 and 70, secured by a nut 71. The upper end of the shaft is journaled in a transverse arm 72 secured on the table, as at 73 and 74, and rising above and bridging over the disk 68.

The upper inner end of each weight 46 carries a roller 75 (Figs. 1, 2 and 5), adapted to run on the cam 39 at each rotation of the disk 33 and so raise the weight.

Turning now to Figs. 3, 4 and 6, each hole 41 in the ring flange 40 is continued in a circumferential direction at the one side thereof in appropriate slots 76 and 77. Across the upper portion of the upper slot 76 is set a square shaft 78 carrying at its center in the slot 76 a piece 79 with a corresponding square hole therein and to which is secured an elongated spring catch 80 operating in the lower slot 77.

The outer end of each square shaft 78 carries an arm 81, the outer end of which has a radially set roller 82 thereon. A spring 83, the lower end of which is secured to the ring flange 40, is steadily pulling the arm 81 in a downward direction and against the stop 42^a which may be the screw securing the respective tube 42.

The square shaft 78 is set into two bush-

ings 84 and 85 (Fig. 6) set in the portion of the flange 40 between the piece 79 and the arm 81 on the one side, and said piece and the nuts 86 on the other side so that by tightening said nuts the whole structure will be fixed and will be rotatable in the flange 40.

5 A housing 87 is secured on the table 20 near the end 53 of the ring 50 slidably housing a vertical piece 88 the top of which carries a cam 89, the location of which is best shown in Fig. 1.

10 Fig. 7 shows the inside of the housing with its front cover removed and it will be seen that a slot 90 is provided in the piece 88 and an eccentric cam 91 is operating in said slot set on a square shaft 92. Said square shaft carries an arm 93 at its outer end (Figs. 3 and 8) and it will be obvious that turning the arm upwardly in the direction of arrow 94 into its dotted position will turn the eccentric and lower the cam 89 into its dotted position see Fig. 3, the lowering of said cam being necessary when it is desired to put the same out of operation. Bushings 95 and 96 and nuts 97 may be provided to secure the parts together and journal the shaft in the housing 87 in a similar manner to the construction on the shafts 78 of the spring catches 80 described hereinbefore.

15 The operation of my device is as follows:

20 The cork rods 43 will be pushed down through the tubes 42, the upper spring catches 45 permitting their downward movement and the star wheels rotating in their weights, while the rods 43 slide downward. When all the tubes 42 are filled the ring 33 and knife 68 are set into rotation and the portions of the rods between the top of ring 50 and the knife 68 will be cut off.

25 Taking one rod 43 as an example, after the cutting operation it will travel around supported by the lower spring catch 80. When it reaches the inner cam 39, the roller 75 on its weight 46 will ride on the cam and raise the weight in relation to its cork rod 43. When the respective rod 43 reaches the outer cam 89 the roller 82 on the arm 81 of the lower spring catch 80 will run thereon and releases the rod 43 from said catch, as it will be obvious by inspecting the drawings. The rod under the influence of its weight 46 will drop down onto the stationary ring 50 and another cork disk will be sliced off from its bottom end by the knife 68, after which the play repeats itself. The continuous raising of the weight is necessary as otherwise it soon would reach the top of the flange 40, would come to rest thereon and would not lower the rod 43 any longer. While the weight is permitted to sink it will be fixed to the rod since the star wheels 49 are prevented from rolling on the rod 43 in the direction corresponding to the sinking of the weight by their spring ratchet 98. (Fig. 5.)

30 It will be obvious that the thickness of the

cork disks cut may be regulated to any desired degree through the bolts and nuts 51 and 52, by raising or lowering the stationary ring 50.

The outer bottom circumference of the ring 33 may show the counter sunk ring 99, (Figs. 2 and 5) the inner portion of it being also countersunk as at 100, so as to leave only two comparatively narrow ring lugs 101 and 102 whereby the engagement of the knife disk 68 therewith will be greatly improved.

10 An opening 103 (Fig. 1) may be provided in the table 20 underneath the place where the actual cutting takes place, said opening having a chute 104 thereunder guiding the ready cork disks 105 into an appropriate container 106.

15 To continually keep the knife 68 in a first class condition, I provide automatic continuously operating sharpening means, indicated in general by the character 107 at the lower right hand end of Fig. 1. Said sharpening means comprises a standard 108 (Figs. 1 and 9) having a transverse piece 109 thereon which carries the adjustable frames 110 and 111 with the abrasive disks 112 and 113 rotatable around shafts 114 and 115 and pressed by springs 116 and 117 against the two sides of the knife disk 68.

20 Since by continuous use and sharpening the knife disk 68 may become so small in diameter that it will not reach the rod 43 while yet supported at the end 53 of the stationary ring 50, to overcome this difficulty I provide a sliding piece 118 in the top of ring 50 at its end 53 adjacent to the place where the rods 43 approach the knife 68 (Figs. 1, 4 and 10), said piece being secured in its place by a screw 119 operable in a slot 120 in the ring 50. When the knife 68 is too much worn, screw 119 will be loosened, piece 118 advanced, and then secured again.

25 A cylindrical housing 121 also may be provided to protect the knife 68.

30 What I claim as new, is:

1. In a device of the class described, an element carrying a plurality of rods; a cutting element, the two having overlapping movements one against the other so as to intermittently cause a portion of the rods to be sliced off; means to intermittently advance the rods to a desired limit, said means including weights secured to the rods to urge them towards the cutting element by gravity action, and means to intermittently move said weights along the rods away from the cutting element.

2. In a device of the class described, an element carrying a plurality of rods; a cutting element, the two having overlapping movements one against the other so as to intermittently cause a portion of the rods to be sliced off; means to intermittently advance the rods to a desired limit, said means including a weight for each rod to move the rod

towards the cutting element by gravity action, star wheels rotatably arranged in said weight and engaging said rod with their teeth, being adapted to rotate when the weight is moved away from the cutting element, but being prevented from rotation when the weight is moved in the reverse direction towards the cutting element, and a stationary cam engaging said weights and moving them away from the cutting element when the respective rod passes the cam.

Signed at New York, in the county of New York and State of New York, this 30th day of August, A. D. 1928.

BERTHOLD NAGY.
